United States Patent Office.

ISAAC W. BROWN, OF NEW HAVEN, ASSIGNOR TO HIMSELF AND GEORGE D. NETTLETON, OF FAIR HAVEN, CONNECTICUT.

Letters Patent No. 74,295, dated February 11, 1868.

IMPROVEMENT IN MOTIVE-POWER.

The Schedule referred to in these Letters Patent and making part of the same.

TO ALL WHOM IT MAY CONCERN:

Be it known that I, ISAAC W. BROWN, of New Haven, in the county of New Haven, and State of Connecticut, have invented a new and improved Motive-Power; and I do hereby declare that the following is a full, clear, and exact description thereof, which will enable those skilled in the art to make and use the same, reference being had to the accompanying drawings, forming part of this specification.

This invention relates to a new and improved method of propelling machinery of all kinds, and it is designed as a substitute for steam, water, horse, or other motive-power, for driving steamboats, locomotives, and stationary machinery; and the invention consists in applying the reacting force or power of India-rubber belts or bands to that purpose, in the manner hereinafter described.

In this example of my invention, the power is applied to a clock-movement; but this particular application is made merely to show and illustrate its adaptability to other purposes.

Figure 1 represents a back side view of a clock-movement which is operated by my improved power, showing the manner of its application to that purpose, and how it may be applied to other purposes on a large scale.

Figure 2 is a side view of the same, showing the drum and pulleys on which the India-rubber band is confined.

Figure 3 is a front view of the same, showing the clock-escapement and the parts connected therewith. Similar letters of reference indicate corresponding parts.

As far as regards the machinery or parts of this clock-movement, there is no novelty claimed.

A represents the frame which supports the drum and wheel and arbors of the movement. B is the drum, which is made to revolve on the arbor or shaft C, which drum is held by a ratchet and pawl, b, seen in the drawing. The wheels and pinions, by which motion is imparted to the escapement f, are seen, marked g, in the drawing. H represents the rubber spring, which is made of one or more strips or pieces of India rubber.

In practice, I have found that a cluster of rubber cords or threads of greater or less diameter or size affords the necessary elasticity and reactive force; but the rubber may be in any form which may be considered best adapted to the purpose intended, either a cluster of cords, as represented in the drawing, or a cluster or combination of bands in the form of rubber tape or ribbons; or a single band or piece of rubber may be employed, as may be desired. In this description, it will be treated as a single band or belt. One end of this band is firmly attached to the drum B; and in its relaxed state the band is carried over the loose pulleys J J, and the other end is firmly secured to a cross-bar, K, in the frame A, as seen in the drawing. This arrangement in the clock-movement allows of a great length of belt, and consequently of a greater reservoir of power than a shorter band would.

In applying the power to driving machinery, or as a substitute for the steam-engine or other motive-power, the length of the band might be extended to any desired extent, thereby insuring a continuance of the reactive force for a period of time corresponding with the requirement of the service to be performed. When the rubber belt is thus securely fastened at each end, it is wound upon the drum B by revolving the same by the key, or by a crank, or in any convenient manner, when the power is applied on a larger scale.

It will of course be understood that the amount of power thus stored up will depend upon the tension given the band, and that the recoil or reaction of the band acts directly upon the gear-wheels of the machinery by revolving the drum-shaft C, from which motion and power are imparted.

Having thus described my invention, I claim as new, and desire to secure by Letters Patent—

The elastic band H, in combination with the gearing, substantially as herein described, for the purpose specified.
